UNITED STATES PATENT OFFICE

137,993

DESIGN FOR AN ADVERTISING RACK

Nicolas Bencomo, Tampa, Fla.

Application December 1, 1943, Serial No. 111,860

Term of patent 14 years

(Cl. D1—2)

To all whom it may concern:

Be it known that I, Nicolas Bencomo, a citizen of the United States of America, residing at Tampa, county of Hillsborough, and State of Florida, have invented a new, original, and ornamental Design for an Advertising Rack, of which the following is a specification, reference being had to the accompanying drawing, forming a part thereof, wherein the figure is a perspective view of an advertising rack, showing my new design.

I claim:

The ornamental design for an advertising rack, as shown.

NICOLAS BENCOMO.
